UNITED STATES PATENT OFFICE

169,005

TRUNDLE TOY

Noel S. Leckness, Kansas City, Kans.

Application December 12, 1951, Serial No. 17,703

Term of patent 7 years

(Cl. D34—15)

To all whom it may concern:

Be it known that I, Noel S. Leckness, a citizen of the United States, residing at Kansas City, in the county of Wyandotte and State of Kansas, have invented a new, original, and ornamental Design for a Trundle Toy, of which the following is a specification, reference being had to the accompanying drawing, forming a part thereof.

Fig. 1 is a side elevational view of the trundle toy, showing my design;

Fig. 2 is a top plan view thereof; and

Fig. 3 is a front elevational view thereof.

I claim:

The ornamental design for a trundle toy, as shown.

NOEL S. LECKNESS.
